UNITED STATES PATENT OFFICE.

CHARLES A. STOCKSTROM, OF ST. LOUIS, MISSOURI, ASSIGNOR OF ONE-HALF TO LOUIS STOCKSTROM, OF SAME PLACE.

DESIGN FOR A VAPOR-BURNER CAP.

SPECIFICATION forming part of Design No. 17,752, dated September 27, 1887.

Application filed July 26, 1887. Serial No. 245,384. Term of patent 7 years.

To all whom it may concern:

Be it known that I, CHARLES A. STOCKSTROM, a citizen of the United States, residing at St. Louis, in the State of Missouri, have invented and produced a new and original Design for a Vapor-Burner Cap, of which the following is a specification, reference being had to the accompanying drawings, forming part thereof.

Figure I is an upper or top perspective view of my improved burner-cap; and Fig. II is an under perspective view, the burner-cap in this view differing slightly from the form shown in Fig. I.

My design consists in a disk, 4, having downwardly-extending flange 5, marked with vertical lines 6, representing slits or openings, the whole superposed centrally upon a disk, 1, having downwardly-extending flange 2,

marked with vertical lines 3, representing slits or openings. Beneath the flange 2 is shown an annular band, 8, and represented within the band is a ring, 7, and a small disk, 9, with arms, and shown as supported by a bolt, 10, and nut 11.

I claim as my invention—

The design for a vapor-burner cap herein shown and described, the same consisting of a disk, 4, having downwardly-extending flange 5, marked with vertical lines 6, the whole superposed centrally upon the disk 1, having downwardly-extending flange 2, marked with vertical lines 3.

CHAS. A. STOCKSTROM.

In presence of—

GEO. H. KNIGHT,
EDW. S. KNIGHT.
